UNITED STATES PATENT OFFICE

JOHN RAY ULRICH, OF BETHLEHEM, PENNSYLVANIA, ASSIGNOR TO BETHLEHEM
STEEL COMPANY, A CORPORATION OF PENNSYLVANIA

RAILWAY TRACK STRUCTURE

Application filed October 25, 1929. Serial No. 402,412.

My invention relates to railway frogs and particularly to jump frogs for turnouts for use with continuous main track rails.

Heretofore it has been the practice, where turnouts are provided for transferring a train from one track to another to place a frog in the main track at the point where the tracks cross, or to provide a crossover which was adaptable to be moved into and out of contact with the main rail when it was desired to keep the rails of the main track continuous so that there will be no interference with the wheels of a train passing along the main track.

In one case it was necessary for the flanges of the wheels of a train passing along the main track to contact with the frog, therefore imparting jars to the cars and wear to the frog, and in the other case it was necessary for a section of the crossover to be moved into contact with the main rail each time the switch was thrown to allow a train to pass from the main track onto the siding or to pass from the siding onto the main track and then to be moved out of contact with the main rail so as to permit a train to pass along the main track.

It is therefore the object of my invention to provide a jump frog at the point where the turnout crosses the main rail which may be placed into engagement with a main rail at any point along the main track without any alterations to the main rail and which will not interfere with the wheels of a train passing over the main track.

Another object of my invention is to provide a jump frog which can be quickly moved from one location to another whenever it is desired to change the location of the turnout.

Another object of my invention is to provide the jump frog with an extension to which the adjoining rail may be fastened preferably without the use of fish plates.

The novel features of my invention will be more fully understood from the following description and claims taken with the drawings, in which:

Fig. 1 shows a section of track with a turnout embodying my improved jump frog.

Fig. 2 is a top plan view of my improved jump frog.

Fig. 3 is a cross section taken along line 3—3 of Fig. 2.

Fig. 4 is a cross section taken along line 4—4 of Fig. 2.

Fig. 5 is a cross section taken on line 5—5 of Fig. 2.

Referring to the drawings more in detail, 10 and 11 designate the rails of a main track 60 which may be of any construction. Associated with the main rails 10 and 11 are pivoted switch points 13 and 14, respectively, the switch point 13 being constructed to abut the side of the rail 10 and the switch point 14 65 to overlie the rail 11 when the switch is operated to the position shown in Fig. 1 of the drawings. The end of the switch point 14 is beveled so that the wheel of a train may easily pass onto or off of the switch. The switch 70 points 13 and 14 are connected to the turnout rails 15 and 16, respectively. These rails as well as rail 15a are supported and held in their proper spaced relation by means of the ties 17. The ties 17 are provided with chairs 75 18 upon which the rails 15, 15a and 16 are placed so as to elevate them the required amount.

The rails 15 and 15a are terminated a sufficient distance from the main rail 11 to allow 80 my improved jump frog 20 to be inserted so as to provide means to permit the wheels of a train on the turnout to pass over the continuous main rail.

My improved jump frog 20 preferably 85 comprises a pair of members 21 and 22 which are adapted to engage the fishing surface of the main rail 11. The members 21 and 22 are preferably provided with integral extensions 90 23 and 24, respectively, which are adapted to engage the fishing surface of the rails 15 and 15a, respectively, and are provided with apertures 25 and 26, respectively, to receive suitable fastening means for connecting them to the rails 15 and 15a.

A plate 27, which is operatively attached to one of the members, preferably in fixed relation therewith, by any suitable fastening means, such as rivets, bolts, or welds, and which is provided with means for receiving 95 100

fasteners such as clips for clamping the other member thereto, is provided for the purpose of connecting these members in their proper relation to each other and with the main rail 11 when they are in their assembled condition.

The member 21 is provided with a tread portion 29 which is preferably in the same plane as the upper surface of the head of the turnout rail 15 when it is assembled therewith, a rail engaging portion 30 which is adapted to engage the fishing surface of the rail 11 and a web portion 31 which connects the tread portion 29 and the portion 30 and 10 also performs the function of spacing the portion 29 the required distance from the main rail so as to provide adequate clearance for the flanges of the wheels of a train passing along the main rail 11. The web portion 15 31 lies a sufficient distance below the head of the rail 11 so as to provide adequate space so that the flanges of the wheels of a train passing along the main rail 11 will not come into contact therewith. The member 21 is 20 also provided with outwardly disposed flanged portions 32, 33 and 34 which provide supports for the member 21 and also provide means with which fasteners, such as the clips 35, 36 and 37 may engage.

25 The clip 35 is preferably of the adjustable cam type so that when it is turned on its pivot 38 in one direction it will force the member 21 towards the rail 11 thus causing a gripping action of the members 21 and 22 with the rail 11.

The member 22 is provided with a portion 39 which is adapted to engage the fishing surface of the rail 11, a portion 40, and a tread portion 41 which is preferably in the 40 same plane as the upper surface of the head of the turnout rail 15a when it is assembled therewith. The upper surface of the portion 40 of the member 22 adjacent the head of the rail 11 lies in approximately the same plane 45 as the upper surface of the head of this rail. An upwardly extending guard flange 42, which is preferably integral with the portion 40, is provided as a guard for the wheels of a train passing over the member 22. Flanges 50 43 and 44 extend outwardly from the body of the member 22 and form supports for this member and also provide means for receiving fasteners, such as 45, for attaching the member 22 to the plate 27.

55 From the above it will follow that the wheels of a train passing from the main track 10 onto the turnout, will pass along the rail 15 onto the portion 29 of the member 21 of the jump frog 20, which is in the same plane 60 as the rail 15, until it is over the rail 11 whereupon the flange of the wheel will come into contact with the rail 11 and then the portion 40 of the member 22, which lies in the same plane as the tread of the main rail 11, until 65 the tread of the wheel reaches the portion 41

whereupon the tread will engage this portion and then pass therealong onto the rail 15a which is in the same plane as the portion 41. The portion 41 is tapered towards the main rail 11 and the portion 40 is tapered in the 70 opposite direction so that the wheels will pass onto the portion 41 without shock.

75 While I have shown my invention in but one form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

Having thus described my invention what I claim as new and desire to secure by Letters Patent is:

80 1. In a track structure the combination with continuous main rails, a turnout, a jump frog for said turnout, said frog comprising members which are adapted to engage opposite sides of one of the main rails, a plate associated with said members upon which one of said members is detachably mounted and means associated with said plate adapted to clamp said members into engagement with the main rail.

85 2. A jump frog for a railway track structure, comprising a pair of rail engaging members adapted to engage the sides of a continuous rail, a plate adapted to be operatively connected to one of said members, said plate adapted to pass beneath the continuous rail 90 and to receive the other member and a cam clip pivotally mounted upon said plate adapted to engage the last mentioned member and clamp the pair of members against the continuous rail.

95 3. A jump frog for a railway track structure, comprising a pair of rail engaging members adapted to engage the sides of a continuous rail, a plate adapted to be operatively connected to one of said members, said plate adapted to pass beneath the continuous rail and to receive the other member and fastening means mounted upon said plate adapted to engage the last mentioned member and clamp the pair of members against the continuous rail.

100 4. A jump frog comprising a plurality of members, one of said members adapted to engage one side of a continuous rail, a second member adapted to engage the opposite side of the continuous rail, a plate adapted to pass beneath said members and the continuous rail, said plate adapted to be operatively attached to one of said members, and adjustable fastening means rotatably mounted on said plate adapted to attach the other member to said plate when the members are assembled with the continuous rail.

105 5. In combination with a main track and a turnout therefrom, said main track hav-

ing continuous rails, a jump frog in the turnout intermediate one of said main rails, said frog comprising a pair of members engaging opposite sides of the main rail, a connecting plate for said members, fastening means for securing said plate in fixed relation with one of said members and adjustable fastening means for detachably clamping the other member to said plate and the pair of members to the main rail.

6. In a track structure comprising main continuous rails and a turnout, a jump frog intermediate one of the main rails and the turnout rail, said jump frog comprising a pair of members having portions adapted to engage the fishing surface of opposite sides of one of the continuous rails and portions adapted to engage the fishing surfaces of the rails of the turnout, a plate member adapted to engage the aforementioned members, means adapted to operatively fasten one of the members to the plate member when the frog is in a dismantled condition and adjustable revoluble means mounted on the plate member for fastening the other member to the plate member when the frog is in its assembled relation with the continuous rail.

7. In a railway track structure, a main track, a turnout from said track, said main track comprising continuous main rails, said turnout comprising elevated rails, a jump frog in said turnout adjacent one of the continuous main rails, said jump frog comprising a pair of members adapted to engage the fishing surface of the main rail and means adapted to pass beneath the main rail and connect the members to said main rails without changing the condition of the main rail or the roadbed.

8. In a railway track structure, a main track, a turnout from said track, said main track comprising continuous main rails, said turnout comprising elevated rails, a jump frog in said turnout adjacent one of the continuous main rails, said jump frog comprising a pair of members adapted to engage the fishing surface of the main rail, means adapted to connect the members to said main rails without changing the condition of the main rail, one of said members having a portion of its upper surface in substantially the same plane as the upper surface of the head of the main rail, another portion in the same plane as the turnout rail and an outer guard portion extending upwardly from the portion in the plane with the head of the main rail.

9. In a railway track structure, a main track a turnout from said track, said main track comprising continuous main rails, said turnout comprising elevated rails, a jump frog in said turnout adjacent one of the continuous main rails, said jump frog comprising a pair of members adapted to engage the fishing surface of the main rail, means adapted to connect the members to said main rails

without changing the condition of the main rail, one of said members having a portion of its upper surface in a plane with the upper surface of the head of the turnout rail and in spaced relation with the main rail and another portion intermediate the aforementioned portion and the main rail lying below the under side of the head of the main rail.

10. In a railway track structure, a main track, a turnout from said track, said main track comprising continuous main rails, said turnout comprising elevated rails, a jump frog in said turnout adjacent one of the continuous main rails, said jump frog comprising a pair of members adapted to engage the fishing surface of the main rail, means adapted to connect the members to said main rails without changing the condition of the main rail, one of said members having a portion of its upper surface in substantially the same plane as the upper surface of the head of the main rail, another portion in the same plane as the turnout rail, an outer guard portion extending upwardly from the portion in the plane with the head of the main rail and the other of said members having a portion of its upper surface in a plane with the upper surface of the head of the turnout rail and in spaced relation with the main rail and another portion intermediate the aforementioned portion and the main rail lying below the under side of the head of the main rail.

In testimony whereof I hereunto affix my signature.

JOHN RAY ULRICH.
